UNITED STATES PATENT OFFICE.

AUGUST EDWARD HELD, OF AMSTERDAM, NEW YORK, ASSIGNOR TO STEPHEN SANFORD & SONS, OF SAME PLACE.

DESIGN FOR CARPETING.

SPECIFICATION forming part of Design No. 31,333, dated August 1, 1899.

Application filed July 3, 1899. Serial No. 722,769. Term of patent 3½ years.

To all whom it may concern:

Be it known that I, AUGUST EDWARD HELD, a citizen of the United States, residing at Amsterdam, in the county of Montgomery and 5 State of New York, have invented and produced a new and original Design to be Worked into or upon Carpeting or Similar Fabrics; and I do hereby declare that the drawing accompanying this specification gives and con- 10 veys to any one skilled in the art of carpet-weaving a clear understanding of the same that is sufficient to enable such persons to use my invention.

The said drawing is a face view of the carpet embodying my design, which is charac- 15 terized by Persian set figures and clouded ground, with small ornamental figures on ground, all arranged and treated as shown in the said drawing.

What I claim, and desire to secure by Letters Patent, is—

The design for carpeting substantially as shown and described.

In testimony whereof I have signed my name to this specification in the presence of 25 two subscribing witnesses.

AUGUST EDWARD HELD. [I. S.]

Witnesses:

W. H. SEALEY,

CHAS. A. KENWORTHY.
